UNITED STATES PATENT OFFICE.

MICHAEL CZAP, OF PLEASANT CITY, OHIO.

COMBINED CROSS-TIE AND RAIL-CHAIR.

1,195,445.

Specification of Letters Patent. Patented Aug. 22, 1916.

Application filed March 16, 1916. Serial No. 84,540.

To all whom it may concern:

Be it known that I, MICHAEL CZAP, a citizen of Hungary and resident of Pleasant City, county of Guernsey, and State of Ohio, 5 have invented certain new and useful Improvements in Combined Cross-Ties and Rail-Chairs, of which the following is a specification.

This invention relates broadly to railway 10 crossties, and more specifically to a combined crosstie and rail-chair.

The primary object of the invention is to provide a metallic crosstie having integral seats or chairs for the reception of the track- 15 rails, the same being of simple and durable form.

A further object is to provide, in connection with a combined crosstie and rail-chair, simple and effective means for securing a 20 track-rail in place on said chair.

With these and other objects in view, the invention resides in the features of construction, arrangement of parts and combinations of elements which will hereinafter be exemplified, reference being had to the accompanying drawings, in which—

Figure 1 is a top plan view of the invention showing track-rails mounted thereon; Fig. 2 is a side elevation of the same; Fig. 3 30 is an enlarged detail section taken on line 3—3, Fig. 1; and Fig. 4 is a similar section taken on line 4—4, Fig. 2.

Referring to said drawings, in which like designating characters distinguish like parts 35 throughout the several views, 1 indicates the base and 2 the upright fin of a metallic crosstie which is generally of T shape, said base and fin preferably corresponding in form to the base and web of the usual type 40 of railway track-rail. Formed integral with said crosstie adjacent to each of the opposite ends of the latter is a rail chair, said chairs being designed to constitute seats for the track-rails 3 and being spaced apart an appropriate distance. The chairs are disposed 45 at right angles to the crosstie, and each is of substantially I-beam form in cross section, consisting of a head 4, web 5 and base 6. The opposite ends of each chair project 50 outward a suitable distance beyond the lateral edges of the base 1 of the crosstie, the

chair thus affording a proper capacity for seating the rail.

Formed on the top face of the head 4 in opposing relation are two parallel longitudinally disposed abutments 7 of relatively short length which define a rail-seating space, and provided in said head at points adjacent to each of the opposite ends of said abutments is a vertical opening or aperture 8 designed to receive therein the rail attaching means, the openings at opposite sides of said head being separated a distance equal to the width of the base of the track-rail.

The under sides of the head 4 are inclined 65 with respect to the web 5, the angle of inclination being substantially identical to that of the upper sides of the base-flanges of the track-rail, as is clearly shown in Fig. 3.

The rail attaching means comprises a 70 clamping member 9 of clevis shape having the opposing faces of its side members inclined to correspond with the inclination of the inclined sides of the chair-head and rail-base, above referred to. Said clamp 9, the 75 body of which is of materially less thickness than the width of the opening 8, is introduced in said opening with its side members disposed in embracing relation to the chair-head and rail-base, as shown in Fig. 3, after 80 which a tapered spike, wedge, or key, as 10, is inserted in said opening behind said clamp and is driven downward to wedge the latter into tight gripping relation to the parts embraced by said clamp. As is obvious, the attaching means described will rigidly maintain the seated rail in place on the chair, and, the latter being integral with the crosstie, spreading of the rails is effectually guarded against.

What is claimed is—

A crosstie including a base having a chair, a rigid abutment on the chair head at each side thereof, the abutments being spaced to receive the rail base therebetween 95 and to overhang said rail base, the chair head having a pair of openings on each side thereof and adjacent the respective ends of the abutments, a clamp in each opening engageable with the side edges of the rail 100 base, and also with the upper face of the rail base and the under face of the chair

head, and a key also arranged in each opening and engaged with the clamp whereby upon inner movement of the clamps on either side of the rail the latter will be caused to have its other side edge engaged with the abutment adjacent said other side edge of the rail and its movement arrested thereby.

In testimony whereof, I affix my signature in presence of two subscribing witnesses.

MICHAEL CZAP.
